(57) **CLAIM**

The ornamental design for a wearable radio frequency detector, as shown and described.

DESCRIPTION

FIG. 1 is a front, right, bottom isometric view of a wearable radio frequency detector;
FIG. 2 is a rear, left, top isometric view of the wearable radio frequency detector shown in FIG. 1;
FIG. 3 is a front view of the wearable radio frequency detector shown in FIG. 1;
FIG. 4 is a top view of the wearable radio frequency detector shown in FIG. 1;
FIG. 5 is a rear view of the wearable radio frequency detector shown in FIG. 1;
FIG. 6 is a bottom view of the wearable radio frequency detector shown in FIG. 1;
FIG. 7 is a right side view of the wearable radio frequency detector shown in FIG. 1; and,
FIG. 8 is a left side view of the wearable radio frequency detector shown in FIG. 1.
The broken lines shown in the drawings represent portions of the wearable radio frequency detector that form no part of the claimed design.
